UNITED STATES PATENT OFFICE

FRANK B. KING, OF THREE RIVERS, MICHIGAN

KNOCKDOWN PLAYHOUSE

Application filed January 11, 1929. Serial No. 331,763.

The main objects of this invention are:

First, to provide a knockdown playhouse that is light in weight and simple and economical in construction.

Second, to provide a playhouse that has all taped, hinged joints thereby enhancing the rigidity of the construction when it is erected.

Third, to provide means of retaining the parts when erected.

10 Objects pertaining to details and economies of construction will appear from the detailed description to follow. My improved structure is illustrated in the accompanying drawing, in which:

15 Fig. 1 is a perspective view of my improved playhouse in the erected position.

Fig. 2 is a vertical section taken on line 2—2 of Fig. 1 showing mainly the retaining means for the side walls.

20 Fig. 3 is a reduced end elevation of the playhouse showing the chimney end of the house.

Fig. 4 is a partial sectional view taken on the plane of line 4—4 of Fig. 1 showing the 25 chimney as a locking means for the roof to prevent the lateral displacement of the parts.

Fig. 5 is an enlarged detail section on line 5—5 of Figs. 1 and 2 showing the hinged end roof lug.

30 Fig. 6 is a general view of the chimney, roof and side wall units in a partially collapsed position, showing how the whole closes into compact form for storage or shipment.

35 The parts will be identified by their numerals of reference which are the same in all the views.

The playhouse is composed of a wall unit 40 comprising front wall section 1 having a door 11 therein secured by tape hinge 12, side walls 2 of different height scored centrally at 21 to facilitate the folding thereof, and the back wall section 3 with a chimney 31 painted thereon.

45 The roof 4 is scored at 42 at the ridge for folding. Side wall retaining lugs 43 are hinged thereto at the sides and end wall lugs are hinged towards the front end of the roof, see Fig. 5. A plurality of slots 44 are provided in the roof at the back to accommodate

the chimney 5 which is a collapsible open ended box.

50 5 are the tapes at the corners or hinge members, which strengthen the structure and facilitate the easy folding of the same. The 55 playhouse can be easily collapsed into small space for storage or shipment.

When the wall unit is set up the sides which are scored at 21 are retained in place by the hinged stop members 43 secured to the under 60 side of the roof. These members lie in a plane parallel to the side wall and prevent the same from buckling inwardly as would be the natural tendency.

65 The walls of chimney 5 engage the slots 44 and overhang the peak of the rear wall, thereby locking the same in place and also preventing the roof from shifting laterally.

Having thus described my invention, what I claim as new and desire to secure by Letters 70 Patent, is:

1. In a knockdown playhouse, the combination of gable end and side walls hinged to each other at the corners, the side walls being centrally vertically scored to collapse inwardly, 75 the end wall being provided with a door with tape hinge adapted to collapse, a collapsible roof made up of side sections and scored to hinge at the peak, the said roof being slotted transversely at the ridge opposite the end wall, a chimney the walls of which are adapted to engage the said slots and interlock with the gable peak of the end wall, hinged lugs at the sides of said roof to engage the inner sides of the side walls opposite the hinged scoring, 80 and hinged lugs at the ends for supporting the end walls and preventing their collapse inwardly, as described.

2. In a knockdown playhouse, the combination of gable end and side walls hinged to each other at the corners, the side walls being centrally vertically scored to collapse inwardly, a collapsible roof made up of side sections and scored to hinge at the peak, the said roof being slotted transversely at the ridge opposite the end wall, a chimney the walls of which are adapted to engage the said slots and interlock with the gable peak of the end wall, hinged lugs at the sides of said roof to engage 95 the inner side of the side walls opposite the 100

hinged scoring, and hinged lugs at the ends for supporting the end walls and preventing their collapse inwardly, as described.

3. In a knockdown playhouse, the combination of gable end and side walls hinged to each other at the corners, the side walls being centrally vertically scored to collapse inwardly, a collapsible roof made up of side sections and scored to hinge at the peak, the said roof being slotted transversely at the ridge opposite the end wall, a chimney the walls of which are adapted to engage the said slots and interlock with the gable peak of the end wall, and hinged lugs at the sides of said roof to engage the inner sides of the side walls opposite the hinged scoring, as described.

4. In a knockdown playhouse, the combination of gable end and side walls hinged to each other at the corners, the side walls being centrally vertically scored to collapse inwardly, a collapsible roof made up of side sections and scored to hinge at the peak, the said roof being slotted transversely at the ridge opposite the end wall, a chimney the walls of which are adapted to engage the said slots and interlock with the gable peak of the end wall, and hinged lugs at the sides of said roof to engage the inner sides of the side walls, as described.

In witness whereof I have hereunto set my
30 hand.

FRANK B. KING.
